UNITED STATES PATENT OFFICE

2,541,669

LOCKING CLIP FOR PENS

Anthony G. Rosa, Lyndhurst, N. J.

Application July 26, 1945, Serial No. 607,237

1 Claim. (Cl. 24—11)

1

This invention relates to new and useful improvements in locking devices for fountain pens and pencils, and it has for its object to provide a locking member that will prove infallible in operation, sturdy in use, easy to manipulate, and cheap to manufacture.

With the above and other objects in view, this invention consists of the novel features of construction, combination and arrangement of parts, hereinafter fully described, claimed and illustrated in the accompanying drawing, forming part of this specification, and in which similar characters of reference indicate corresponding parts in all views, and in which:

Figure 1 is a partly elevational and partly transverse sectional view, showing my locking device attached to the upper closure member of a fountain pen.

Figure 2 is a view similar to Figure 1, showing my locking device engaging a pocket.

Figure 3 is also a view similar to Figure 1, showing my locking device in the process of disengagement from the pocket.

Figure 4 is a side elevational view of said closure member, or cap, with the locking device secured thereto.

Figure 5 is a side elevational view of my device, as disclosed in Figure 1.

Referring more particularly to the drawing, the numeral 10 indicates the rather conventional clip member, generally attached to the outside of the upper closure cap 11 of a fountain pen and secured to said closure cap by means of screws or bolts 12. A spring member 13 is attached to the inner side of said closure cap 11, for instance by means of the same bolts 12.

A stud 14 is fixedly secured to the spring member 13 and protrudes through openings 15 and 16 in the closure cap 11 and the clip member 10, respectively, as may be seen especially in Figure 2.

An upwardly projecting tapered stud 17 forms an integral part of the spring member 13 and protrudes through an opening 18 in the closure cap 11 for the purpose of engaging a pocket 19, as shown in Figure 2, when a fountain pen or pencil is placed in said pocket.

The spring member 13 terminates at its lower end in an angularly bent hook portion 20 adapted to solidly engage the top of a fountain pen by means of an annular recess 21 in the latter, when the fountain pen is inserted into a pocket, as

2

shown in Figures 2 and 3, thereby securing a safe attachment of the ensemble of a fountain pen and its closure cap to a garment.

The locking device is applied to a pocket 19 by means of the stud 17 upon insertion of a fountain pen into said pocket, as shown in Figure 2; it is disengaged from the pocket by applying pressure to the stud 14 by a finger 22, as shown in Figure 3.

10 It is obvious that changes may be made in the form construction and arrangement of the several parts, as shown, without departing from the spirit of the invention, and within the appended claims, and I do not, therefore, wish to limit myself to the exact construction shown and described herein.

What I claim as new, and desire to secure by Letters Patent of the United States, is:

20 The combination of a fountain pen, having an annular groove therein, with a closure cap, the latter being formed with two cut-outs in the side thereof, a clip having a hole therein and being secured to the outside of said closure cap, a spring secured to the inside of the latter, a tapered stud fixedly attached to said inner spring and extending through out of the openings in the closure cap, a second stud fixedly attached to said inner spring and protruding through the other opening in the closure cap and through the hole in said clip, said inner spring terminating in a hook portion adapted to engage the groove in the fountain pen, substantially as shown and described.

ANTHONY G. ROSA.
